IMITATION PINKED PIPING

Filed Sept. 26, 1938

UNITED STATES PATENT OFFICE

2,211,707

IMITATION PINKED PIPING

René Marc Sichère, Long Island City, N. Y.

Application September 26, 1938, Serial No. 231,636

10 Claims. (Cl. 91—14)

My invention relates to the art of ornamenting material for use in making articles of wearing apparel.

The object of my invention is to provide a machine for making pinking piping by the use of a stain or plastic applied to the margin of a sheet of material such as leather, that will be a close imitation of the pinking piping as heretofore made by the use of a separate strip of material attached to the sheet.

A further object is to provide an imitation pinking piping by applying to the margin of a sheet of material a band of color and notching said band and sheet to provide a serrated edge which simulates a pinking piping.

A further object of my invention is to provide a new process for ornamenting the marginal portions or portion of a sheet of material such as leather, by the use of a paint or stain and simultaneously cutting thru the sheet and painted portion by the use of a serrated wheel which forms an uneven edge and provides an imitation pinking piping.

Referring to the drawing which forms a part of this application:

Fig. 1 is an elevational view of a machine, shown partly in section, used in making said imitation pinking piping.

Fig. 2 indicates a fragmental portion of a wheel having a serrated periphery which cuts thru the material to make an edge portion thereof to provide a pinking edge.

Fig. 3 is a plan view of a portion of the wheel shown in Fig. 2 showing the form of the cutting edge of the wheel.

Fig. 4 is a side view of the imprinting wheel, shown on an enlarged scale.

Fig. 5 is a plan view of a portion of the imprinting wheel having a serrate or roughened tread surface, and having a side portion adjacent thereto which is formed to provide a toothed gear.

Fig. 6 is a plan view of a portion of a sheet of material such as leather, illustrating the pinking piping as it appears when made in successive operations.

Fig. 7 is a plan view of the sheet illustrative of the appearance of the margin as it appears when made complete in a single operation which consists of applying the band of paint to the margin of the sheet and simultaneously forming the pinking edge in the act of cutting thru the sheet.

In carrying my invention into practice, I prefer to complete the work in one operation where the width of the stripe portion thereof is predetermined, but in the case where the width of the

stripe portion is not predetermined I prefer to complete the work by a second step or steps, as hereinafter set forth.

The imitation pinking piping is made without the use of a separate strip of material such as required in making standard pinking piping, and therefore the thickness of the marginal portion of the sheet is not increased perceptibly over that of the uniform thickness of the sheet as a whole.

The imitation pinking piping comprising an edge portion of sheet material that is uneven in form, and is provided by applying a stripe of paint or stain of predetermined width in the form of a band to the surface of the sheet and simultaneously or successively dividing the sheet by the use of a serrated wheel which cuts thru the striped portion and provides an edge which imitates a pinking piping of the usual construction.

The width of the band portion depends upon the depth and width of the notches formed in the material, and the color may be such as to harmonize with the color of the sheet, or of any color other than that of the material to which it is applied, and in some cases may be of the same color but of a different tint or effect.

Referring to the machine used in making the herein described product,

10 indicates a table the top of which is made of smooth metal.

11 indicates a frame mounted on the table and having an arm 12 which extends over the table a predetermined distance therefrom.

13 indicates a shaft which may be rotated in any desired manner, and a wheel 14 is mounted thereon and driven thereby.

The periphery of the wheel 14 rests in contact with the top of the table 10, and is hereinafter referred to as the cutting wheel.

The cutting wheel 14 is formed to provide a serrated or notched outer rim portion 14' which serves to cut thru and divide the sheet 15 in forming the serrated edge of the sheet, said notched portions extending from the outer edge of the wheel toward the axis thereof and serving as gear teeth to mesh with and drive the adjacent wheel 23 which is provided with corresponding teeth.

The upper portion of the frame 12 carries a lever 16 which is hinged to the frame at 17 and carries an arm 18 in hinged relation at 19, both lever and arm having an upturned portion at its free end connected together by a spring 20 which serves to pull said end portions toward each other and thereby cause engagement of the adjacent wheels.

Carried by the arm 18 is a two-part housing 21 formed to provide a circular chamber 22 having parallel side walls between which is closely mounted a wheel 23 which extends below the 5 casing or housing and is carried in inclined relation to the wheel 14, and has serrations or teeth 24 corresponding to those formed in the side of the wheel 14 and fitted to mesh loosely therewith and permit a certain amount of upward movement of the housing and wheel 23 relative to the 10 wheel 14 while the gears are in mesh and the wheels are rotating in unison.

The outer periphery of the imprinting wheel 23 extends laterally a distance from the serrations 15 in its sides to provide an unbroken tread portion 24 which is spaced from the table top a distance corresponding to the thickness of the material 15 and the tread portion is roughened and serves to carry the paint and press it upon the sheet in 20 the form of a band, and also serves to grip the surface of the sheet and aid in moving it in the act of cutting it and forming the pinking.

The housing is formed with a conduit 21' on 25 the upper end of which is carried a cap 25 which supports the paint receptacle 26

The paint or stain is very fluid and flows freely from said receptacle thru the conduit to the top of the wheel 23 and is carried thereby in the serrations 24' to the work as the wheel is rotated, 30 the paint being forced against the cutting edges of the wheel 14 and laterally under the tread surface 24 of the wheel 23, as will be readily understood.

A spring 27 connected to the frame 11 and 35 lever 16, is under tension and serves to hold the wheels 14 and 23 constantly in mesh regardless of the thickness of the sheet 15, the thickness of the sheet serving to automatically position the wheel 23 relative to the wheel 14.

The housing is easily detachable from the lever 40 16 for the purpose of cleaning or for changing for another housing having a wheel provided with a different width of treat surface, and also is free to be swung outward from the wheel 14 for cleaning or inspection.

28 indicates the strip portion removed from the sheet in the cutting operation.

In Fig. 6 the band of paint is made wider for 45 the purpose of forming a colored portion on both the sheet 15 and strip 28 cut therefrom in the process where the pinking is done in a subsequent step, this method serving to provide a separate strip having a pinked edge that is colored, and which may be used as an ornamental trimming, 55 and if the strip portion is of sufficient width, to provide two sheets of finished material.

When the sheet is finished by a simultaneously 50 operation in which the paint is applied at the same time that the sheet is cut thru and the pinking operation is performed, the paint is applied at one side only of the cutting wheel by the imprinting wheel, leaving the strip portion practically free from paint.

In operating the machine I prefer to use a 60 small motor to rotate the shaft.

The rotation of the shaft drives the meshed 65 wheels in unison and the sheet is fed under them and automatically advanced as the paint 29 is applied by the imprinting wheel and the sheet 70 divided in the act of forming the pinked edges in the sheet and strip, or in both sheets when the process is carried out in two operations as hereinbefore described.

If desired, a line of stitching 30 may be applied 75 adjacent the edge of the stripe, or such a line

may be imprinted by the imprinting wheel to simulate a stitching, and thus further simulate a pinked piping as heretofore made.

Having thus described my invention I claim as new:

1. A machine of the character described comprising a frame and table portion, a rotatable shaft carried by the frame and extending over the table, a pinking wheel carried on an end of the shaft, said wheel having its periphery formed 10 to provide a serrated cutting edge which is positioned adjacent the top of the table, a housing, an imprinting wheel carried therein the lower end of which extends below the housing in co-operative relations with said pinking wheel. 15

2. The construction defined in claim 1, together with; said housing having a conduit to receive and lead a liquid from a source of supply to the periphery of said imprinting wheel.

3. A machine of the character described comprising a frame and table portion, a rotatable shaft extending from the frame over said table, a pinking wheel carried by said shaft having its periphery formed to provide a serrated cutting edge which is positioned adjacent the top of the 20 table, a bell-crank lever hinged to said frame, and arm hinged to and carried by said bell-crank lever with a free end thereof extending opposite to the free end of said bell-crank lever, a spring located between the free ends of said lever and arm which serves to draw them toward each other, a housing carried by said arm and formed to provide a circular chamber having parallel side walls, a serrated imprinting wheel fitted in said 25 chamber and extending thru the lower side thereof of a predetermined distance into co-operative relation with said pinking wheel.

4. The construction defined in claim 3 together with a spring connected to the bell-crank lever and frame which serves to force said imprinting 30 wheel against said pinking wheel.

5. The construction defined in claim 1, together with; said wheels being meshed at their point of juncture.

6. A machine of the character described comprising a frame and table portion, a rotatable shaft carried by the frame and extending over the table, a pinking wheel carried by the shaft and formed with a serrated cutting edge, said serrations extending from said cutting edge toward the 45 axis of the wheel and serving as a driving gear, a housing supported by the frame in swinging relation thereto, an imprinting wheel carried by the housing in an inclined position relative to the pinking wheel, and having a tread surface formed 50 in its outer periphery, and formed with serrations in a side thereof which extend toward the axis of the wheel and mesh with the serrations formed in the pinking wheel.

7. The construction defined in claim 6, together 55 with; said housing having a conduit leading to the tread surface of the imprinting wheel, and a receptacle for liquid carried by said housing at the upper end of said conduit.

8. The construction defined in claim 6, together 60 with; and means carried by said frame for forcing said imprinting wheel into engagement with said pinking wheel whereby it may be driven by said pinking wheel.

9. A machine of the character described comprising a frame and table portion, a rotatable shaft carried by the frame and extending over the table, a pinking wheel carried on an end of said 65 shaft and formed to provide serrations which extend from the edge of the wheel toward the 70 75

axis thereof a predetermined distance, an imprinting wheel supported at an incline to the pinking wheel and formed with corresponding serrations to those formed in the pinking wheel, said wheels normally resting in geared relation, and means for leading a liquid from a source of supply to the imprinting wheel.

5 10. The construction defined in claim 9, to-

gether with; said supporting means for the imprinting wheel comprising hinged levers and a housing, said levers serving to permit said housing to swing outward from the pinking wheel, and move upwardly while in engagement therewith.

RENÉ MARC SICHERE.
